UNITED STATES PATENT OFFICE.

HARRY C. WILSON, OF NEW YORK, N. Y.

ADJUSTABLE DRESS-CHART.

SPECIFICATION forming part of Letters Patent No. 664,700, dated December 25, 1900.

Application filed January 22, 1900. Serial No. 2,341. (No model.)

To all whom it may concern:

Be it known that I, HARRY C. WILSON, a citizen of the United States, residing in the city of New York, borough of Manhattan, in 5 the county and State of New York, have invented new and useful Improvements in Garment-Cutting Patterns, of which the following is a full, clear, and exact description.

My invention relates to garment-cutting 10 patterns, and has for its object to provide a series of adjustable patterns that may be readily set according to measurements, so as to obtain proper patterns for a lady's waist, the principal aims of my invention being to 15 simplify the adjusting operations, to provide a construction that will positively give the full outline of each piece, and to enable the dressmaker to vary the pattern so as to give greater or less width to certain portions of 20 the waist.

As my improved pattern gives the complete outline of each piece and not only points thereof which require to be connected by lines, it will be obvious that the pattern may be 25 used for tracing the outline of the several pieces directly on the material from which the waist is to be produced.

My invention will be fully described hereinafter, and the features of novelty pointed 30 out in the appended claims.

Reference is to be had to the accompanying drawings, forming a part of this specification, in which similar characters of reference indicate corresponding parts in all the views.

35 Figure 1 is a plan showing the various sections of my pattern set together as they are used in practice. Fig. 2 is a separate plan, on an enlarged scale, of the front piece of the pattern. Figs. 3 and 4 are sections on the 40 lines 3 3 and 4 4 of Fig. 2. Fig. 5 is a separate plan of the extra under-arm piece, and Fig. 6 shows the under-arm piece.

The entire pattern comprises five different pieces, all of which are used in drafting a waist. 45 These parts are the front piece A, the extra under-arm piece B, (this is not always used,) the under-arm piece C, the form D, and the back piece E.

The front piece A comprises a front end 50 piece A', having pivots a b, on which may turn the dart-pieces A² A³ A⁴, respectively. The pieces A³ and A⁴ are mounted on the

same pivot b, being connected so as to be capable of a limited motion, one relatively to the other, by means of a pin c on one of the 55 said pieces engaging a segmental slot c' on the other piece. Concentric with the pivots a b the front end piece A' is provided with segmental slots a' b', these slots limiting the movement of the projections a² b², secured to 60 the dart-pieces A² A⁴ and forming at the same time pointers indicating on graduations G⁰, disposed adjacent to the said slots. At the front edge said piece A' is provided with a graduation G, which indicates the 65 length of the front, and preferably is so marked. On the upper portion of the front end piece A' is adapted to slide in an inclined direction a neck-piece A⁵, provided for this purpose with slots a⁵, engaged by pins a⁶ on 70 the end piece A'. This neck-piece has two graduations G', adjacent to the slots a⁵, to permit of properly setting the neck-piece relatively to the front end piece. Under the neck-piece and front end piece is located 75 a shoulder-piece A⁶, which along its upper edge has a graduation G² in continuation of the upper edge of the neck-piece, and it is further provided with a slot a⁶, parallel to 80 said graduation and engaged by a pin a⁷ on the neck-piece and with a pin a⁸, engaging a slot a⁹, parallel with the upper edge of the neck-piece A⁵. The shoulder-piece has a curved slot a¹⁰, parallel with its rear edge and engaged by a pin a¹¹ upon an arm-piece A⁷. 85 The arm-piece is connected by a pivot a¹² with the rear dart-piece A⁸, provided with an extension A⁹, guided by means of pins a¹³, engaging a slot a¹⁴. Said extension has a curved rear end intersecting the rear edge of the rear 90 dart-piece A⁸ and indicating upon the graduation G³, provided along said edge. With the rear dart-piece A⁸ is connected the bust-piece A¹⁰ by pins a¹⁶ in the bust-piece and 95 engaging curved slots a¹⁷ in the rear dart-piece A⁸, the center of curvature of said slots being approximately at the pin a¹⁵, carried by the bust-piece. The bust-piece A¹⁰ is formed with two slots a²¹, of which the upper one extends out through the end of the bust-piece, 100 and through said slots the pivot-pins a b pass. The bust-piece A¹⁰ is provided with an extension A¹¹, formed with the slot a¹⁸, through which the pin a¹⁵ and another pin a¹⁹, also

carried by the bust-piece, pass, and the said extension is also formed with slots a^{20} , through which pass the pivot-pins a b after passing through the slots a^{21} of the bust-piece A^{10} .
 5 The slots a^{18} , a^{20} , and a^{21} are all substantially horizontal—that is, parallel with the waist-line. The rear dart-piece A^8 has cut-out portions or slots A^{13} and A^{14} , the cut-out portion or slot A^{13} being under the end of the lower
 10 slot a^{21} and the cut-out portion or slot A^{14} under the slot a^{18} . A^{12} is a reinforcing-piece extending across the front piece A and through which the pivot-pins a b pass. The bust-piece A^{10} is provided along its upper and
 15 lower edges with graduations G^4 , indicating the bust-measure.

The extra under-arm piece B comprises two top sections B' B^2 and two bottom sections B^3 B^4 . The top sections overlap and are adjustable transversely by means of a pin d , engaging a slot d' in the other section, and adjacent to said slot is a graduation G^5 . Each of the top sections is provided with a slot d^2 , extending vertically and engaged by two pins
 25 d^3 on the corresponding bottom sections B^3 B^4 . The top piece B^2 is provided with a further graduation G^6 , and the other top piece B' has a vertical graduation B^7 , on which is adapted to indicate the curved front edge of the bottom piece B^3 . The two bottom pieces are connected by a pin d^4 , engaging a slot d^5 , so that they are adjustable together up and down, but are capable of independent transverse movement.

35 The under-arm piece C is similar in construction to the extra under-arm piece, except that the parts are of slightly-different shape and that there is provided an extra piece C^5 , having slots e^6 , engaged by pins e^7 of the top piece C^2 . The top piece C' has notches e^8 , adapted to receive the pins e^7 when the parts C' C^2 overlap sufficiently. The connections of the several parts have been lettered correspondingly to those of the extra
 40 under-arm piece, and therefore need not be described further. The graduations are as follows: the top graduation G^8 , the waist graduation G^9 , and a rear graduation G^{10} , on which indicates the curved rear edge of the
 45 bottom piece C^4 . The top piece C' has a slot e^9 engaged by a pin e^{10} on the extra piece C^5 .

The form-piece D comprises an upper section D' , having vertical slots f engaged by pins f' on the lower section D^2 , which has a curved edge indicating on a graduation G^{11} on the upper section D' .

The back piece E has two top parts E' E^2 , connected by a pin g , engaging a curved slot g' , and two bottom pieces E^3 E^4 , connected
 60 with each other by pins g^2 , engaging slots g^3 , and to the corresponding top pieces E' and E^2 by pins g^4 , engaging vertical slots g^5 . The back piece has a graduation G^{12} at the top, another graduation G^{13} along its rear edge,
 65 and a third graduation G^{14} adjacent to the connection of the bottom pieces with the top pieces.

In employing my improved pattern the usual measurements are taken and the parts are then adjusted, as best shown in Fig. 1. 70 The extra under-arm piece B is used only for stout forms and is necessary in the example shown for all forms in which the bust-measure exceeds forty-two inches, since this is the limit to which the front piece A may be set. 75 When using the extra under-arm piece B , the bust-piece A^{10} of the front piece A is not adjusted according to the bust measurement, as it is when the extra under-arm piece is omitted; but the amount of sizes represented by 80 the extra under-arm piece will when it is used be deducted from the bust-measure and the bust-piece A^{10} will be set accordingly. This will be best explained by an example. Supposing the bust-measure is forty-seven, the 85 extra under-arm piece B when closed represents seven sizes and may be extended to represent any number of sizes from eight to eleven, as shown in Fig. 5. In Fig. 1 the extra under-arm piece B is so extended as to 90 represent eight sizes. Therefore, the bust-measure being forty-seven, the bust-piece A^{10} will be set to forty-seven minus eight—that is, to "39"—as shown in Fig. 1. The neck-piece A^5 and shoulder-piece A^6 are adjusted 95 according to the shoulder-measure, as indicated by the graduation G^2 , and the front end piece A' is adjusted relatively to the neck-piece A^5 according to the graduations G' . The extension A^9 is set according to the under-arm measure, as indicated upon the graduation G^3 , and the dart-pieces A^2 and A^4 are set so that the pins a^2 b^2 will indicate the same number on the graduations G^{10} , adjacent to the slots a^2 b^2 . The rear dart-piece A^8 and the front dart-pieces A^3 are then turned on their pivot-pins a^{15} and b , respectively, so that the marks "Plain dart" or "French dart" will register with the corresponding outline. Thus in Fig. 1 the dart-pieces A^3 A^8 are set for a 110 French dart, while in Fig. 2 they are set for a plain dart. It will be noticed that with these adjustments all the other parts of the front piece A will assume their proper position, the arm-piece A^7 being shifted, together with the rear dart-piece A^8 . The extra under-arm piece is simply set according to the under-arm measure, it being understood that it lies with the dressmaker's judgment whether the extra under-arm piece shall be 120 made wide or narrow. The under-arm piece C is set at the top according to the arm-size measure and at the bottom according to the waist-measure in width and according to the under-arm measure in length. The form-piece 125 D is simply set according to the under-arm measure. The back piece E is set at the top according to the width of the back, as indicated by the graduation G^{12} ; at the bottom, if desired, according to the graduation G^{14} , and, 130 further, the bottom pieces E^3 E^4 are shoved up or down according to the length of the back, as indicated on the graduation G^{13} .

It will be noticed that two of the pieces are

set according to the waist-measure—namely, the under-arm piece C and the back piece E. In case a narrow back piece is desired the sections of the back piece E are shoved toward each other transversely until they overlap to the fullest extent. In this case the under-arm piece C is set exactly according to the waist-measure. If, however, as on stout forms, it is desirable to make the back piece E wider at the bottom, the sections of the back piece are opened transversely until the proper form has been obtained, as the dressmaker may decide by judgment. Thus in Fig. 1 the back piece has been expanded in width until number "7" is indicated on the graduation G¹⁴. This number is to be deducted from the waist-measure, and supposing this to have been thirty-six it follows that the under-arm piece C will have to be set according to the measure thirty-six minus seven, which is "29," as shown. It will thus be seen that while the several pieces of the pattern give an accurate outline of each piece there is still some latitude left to the skill and judgment of the dressmaker in varying the adjustments of some of the parts.

It will be seen that the manipulations in adjusting the parts of my improved garment-pattern are readily understood, that each part indicates a full outline of the corresponding garment part, and that the pattern may be used for different styles of darts and also allows the dressmaker to use judgment in varying the adjustments of the parts, and thereby secure more perfect results.

Having thus described my invention, I claim as new and desire to secure by Letters Patent—

1. In a garment-pattern, the combination with the front piece, a neck-piece adjustably secured to the front piece, and a shoulder-piece adjustably secured to the neck-piece, of an arm-piece adjustably pivoted to the shoulder-piece, three dart-pieces pivoted to the front piece, two of said dart-pieces being adjustably secured together and mounted on the same pivot, a bust-piece adjustably secured to the front piece, and a rear dart-piece to which the arm-piece is pivoted, adjustably secured to the bust-piece, and provided with an adjustable extension, substantially as described.

2. In a garment-pattern, the combination with a front piece, and dart-pieces pivoted thereto, of a bust-piece provided with aligned guide-pins and with slots through which the pivots of the dart-pieces pass, an extension

for the bust-piece provided with slots to receive the guide-pins and the pivots of the dart-pieces, and a rear dart-piece adjustably secured to the bust-piece, substantially as described.

3. In a garment-pattern, a front piece, three dart-pieces pivoted thereto, two of the dart-pieces being mounted on a common pivot and adjustably connected with each other, an extensible bust-piece adjustably secured to the front piece, a rear dart-piece adjustably secured to the outer end of the bust-piece, a neck-piece adjustably secured to the front piece, a shoulder-piece adjustably secured to the neck-piece, and an arm-piece having one end pivoted to the rear dart-piece and its other end adjustably secured to the shoulder-piece, substantially as described. 75

4. In a garment-pattern, a front piece having curved slots, dart-pieces pivoted to the front piece and each provided with a projection at one end working in a slot of the front piece, a third dart-piece pivoted on one of the pivots of the first-named dart-pieces and adjustably connected with the said dart-piece, an extensible bust-piece adjustably secured to the front piece, a rear dart-piece adjustably secured to the outer end of the bust-piece and provided with an adjustable extension at its lower end, a neck-piece adjustably secured to the front piece, a shoulder-piece adjustably secured to the neck-piece, and an arm-piece having one end pivoted to the rear dart-piece and its other end adjustably secured to the shoulder-piece, substantially as described. 85

5. In a garment-pattern, the combination with a front piece, and pivoted dart-pieces, of a bust-piece provided with slots through which the pivots of the dart-pieces pass and with guide-pins, an extension for the bust-piece provided with slots to receive the guide-pins and the pivots of the dart-pieces, and a rear dart-piece adjustably secured to the outer end of the bust-piece and provided with a lateral extension at its upper end, said extension having cut-out portions or slots to receive one of the said pivots and guide-pins, 105 substantially as described.

In witness whereof I have signed my name to this specification in the presence of two subscribing witnesses.

HARRY C. WILSON.
